[57] CLAIM

The ornamental design for a body waste collection bag stand, as shown and described.

DESCRIPTION

FIG. 1 is a perspective view of a body waste collection bag stand, showing my new design.

FIG. 2 is a front elevational view thereof, the rear elevational view being a mirror image of that shown;
FIG. 3 is a side elevational view thereof, the opposite side elevational view being a mirror image of that shown;

FIG. 4 is a top plan view thereof.

FIG. 5 is a bottom plan view thereof.

FIG. 1

FIG. 3

FIG. 4

FIG. 5

FIG. 2
